(57) **CLAIM**

The ornamental design for a garden hose quick connector, as shown and described.

DESCRIPTION

FIG. 1 is a top perspective view of a garden hose quick connector in a disassembled state, showing my new design; FIG. 2 is a bottom perspective view thereof in a disassembled state;

FIG. 3 is a front view thereof in a disassembled state;

FIG. 4 is a rear view thereof in a disassembled state;

FIG. 5 is a left side view thereof in a disassembled state;

FIG. 6 is a right side view thereof in a disassembled state;

FIG. 7 is a top view thereof in a disassembled state;

FIG. 8 is a bottom view thereof in a disassembled state; FIG. 9 is a top perspective view thereof in an assembled state;

FIG. 10 is a bottom perspective view thereof in an assembled state;

FIG. 11 is a front view thereof in an assembled state;

FIG. 12 is a rear view thereof in an assembled state;

FIG. 13 is a left side view thereof in an assembled state;

FIG. 14 is a right side view thereof in an assembled state;

FIG. 15 is a top view thereof in an assembled state;

FIG. 16 is a bottom view thereof in an assembled state; and, FIG. 17 is an enlarged detail view of area 17 in FIG. 1.

The broken lines in the drawings illustrate the portions of the garden hose quick connector, which form no part of the claimed design.

The dash-dot-dash broken lines encircling the enlarged views are for annotative purposes only and form no part of the claim thereof.

1 Claim, 17 Drawing Sheets
